PANEL FOR LAUNDRY APPLIANCES

Stuart G. Mundt, North Syracuse, N. Y.

Application December 1, 1955, Serial No. 39,126

Term of patent 14 years

(Cl. D49—1)

Figures 2 through 6, are shown on enlarged scales.

I claim:

The ornamental design for a panel for laundry appliances, substantially as shown.
